(57) CLAIM

The ornamental design for a handbag without strapping, as shown.

DESCRIPTION

FIG. 1 is a perspective view of a handbag with strapping showing my design taken from a top left side;

FIG. 2 is a front perspective view thereof;

FIG. 3 is a rear perspective view thereof;

FIG. 4 is a right perspective view thereof;

FIG. 5 is a left perspective view thereof;

FIG. 6 is a top perspective view thereof;

FIG. 7 is a bottom perspective view thereof; and,

FIG. 8 is perspective view thereof taken from a top left side and showing the handbag without strapping in an open position.

The broken lines showing stitching and portions of the handbag are for the purposes of illustrating environment and forms no part of the claimed design.
